DENTAL INSTRUMENT

Lucian G. Coble, Greensboro, N. C.

Application April 6, 1936, Serial No. 73,028

5 Claims. (Cl. 33—143)

This invention relates to a novel dental instrument and particularly to an implement for facilitating the proper positioning of teeth in a denture relatively to the lip line of a patient.

5 In the preparation of a denture for a patient it is, of course, essential that the teeth, and particularly the frontal teeth, be properly located or positioned in the denture with respect to the lips or lip line of the patient. To insure accurate 10 positioning of the teeth in the denture in this respect, the present invention contemplates an instrument by which the distance between the patient's lip and gum can be readily measured and said distance accurately indicated on the 15 denture or the wax mold used in producing the final denture.

A further object is to provide an instrument of this character which is inexpensive and composed of a minimum number of parts, the instrument, as a whole, being very simple and easily manipulated.

More specifically, the invention contemplates an instrument of this nature, composed essentially of a bar having a sleeve slidable thereover 25 with means for clamping the sleeve in any desired position longitudinally of said bar. One end of said sleeve projects beyond the bar and is adapted to be positioned against the gum of the patient while a pin or other projection on the bar 30 is positioned against the patient's lip, the distance between the pin and the gum engaging end of the sleeve denoting the distance between the gum and lip line of the patient. The opposite end of the bar is curved or of hook-like formation to engage in the gum recess of a denture and the spacing of this curved extremity and said sleeve is such as to correspond to the spacing of said pin and the gum engaging end of the sleeve so that 35 40 when the lip line, so-called, of the patient is measured, the sleeve is simultaneously adjusted with respect to the curved extremity of the bar and by placing the curved extremity in the gum recess of the denture or denture mold, the lip line will be indicated on the mold by the position of said sleeve.

With these and other objects in view, the invention consists in certain details of construction and combinations and arrangements of parts, all 45 as will hereinafter be more fully described and the novel features thereof particularly pointed out in the appended claims.

In the accompanying drawing illustrating the preferred embodiment of the invention—

55 Figure 1 illustrates the profile of a patient with

the present instrument in place to measure the patient's lip line;

Fig. 2 is a perspective view illustrating the use of the instrument for denoting the lip line on a denture or denture mold;

Fig. 3 is a vertical sectional view through the instrument and denture mold;

Fig. 4 is a sectional view on the line 4—4 of Fig. 3; and

Fig. 5 is a sectional view transversely of the 10 instrument as indicated by the line 5—5 of Fig. 4.

In the preferred embodiment of the invention, the instrument comprises a rod or shank-like portion 10 on which there is slidably mounted 15 a sleeve 11. Said sleeve is provided with a longitudinal slot 12 for a lateral projection on the rod, said projection consisting of a pin 13 threaded into bar 10 adjacent one end thereof and a thumb screw 14 having a tubular portion 20 threaded on the pin by means of which sleeve 11 may be clamped in any desired position longitudinally of bar 10. The opposite end of bar 10 is offset or curved to form a hook-like portion 15 for purposes which will hereinafter appear. The length of sleeve 11 is such that the distance between the lateral projection on the rod, i. e., the exterior of the tubular portion of screw 14 and the adjacent end of said sleeve corresponds substantially to the distance between 25 the end of the offset portion 15 of said bar and a predetermined point on said sleeve. For instance, in the present construction, the end of the sleeve adjacent hook-like portion 15 is formed with more or less of an annular knife edge 16 30 and the distance between said so-called knife edge and the extremity of hook 15, regardless of the position to which the sleeve may be adjusted on bar 10, substantially corresponds to the distance between screw 14 and the other end of 35 said sleeve. This is made clear in Fig. 3 of the drawing, where the distance between the several points is indicated by the dot and dash lines, the distance between the extremity of hook portion 15 and knife edge 16 being indicated at a 40 and the distance between screw 14 and the adjacent end of the sleeve being indicated at b, these two distances a, b, corresponding to each other.

In the use of the instrument, the end of the 50 sleeve adjacent pin 13 is placed in the mouth of the patient, as indicated in Fig. 1. The end of the sleeve is positioned against the patient's gum with the lateral projection formed by pin 13 and screw 14 positioned against the patient's 55

lip. The sleeve is then clamped on bar 10 by a screw nut 14. With the sleeve locked on the bar in this fashion, the distance between the end of the sleeve and the screw or pin will denote 5 the distance from the patient's gum to the patient's lip line. This distance, as previously pointed out, will also correspond to the distance between knife edge 16 and the offset portion 10 of the instrument. Consequently, after the 10 denture 17 is made up, the hook-shaped extremity 15 of the instrument can be inserted or engaged in the gum recess of the denture mold and by imparting pivotal movement to the instrument with knife edge 16 in engagement with 15 the exterior surface of the mold (Fig. 2), a line 18 can be scored or marked on the mold with the knife edge. This pivotal movement of the instrument takes place with the curved extremity 15 functioning as a pivot, and in view of the 20 fact that the distance between the curved extremity and the knife edge 16 corresponds to the distance between the patient's lip line and the patient's gum, the line 18, indicated on the mold, will mark off the equivalent of the patient's lip 25 line with respect to the gum engaging recess of the mold. In other words, when the teeth are placed in the mold one by one, preparatory to making the ultimate denture, the lower extremities of the teeth will be positioned in registry with the line 18. As a result, when the 30 final denture is made from the mold, the lower extremities of the teeth will register with the lip line of the patient.

While the present instrument is very simple 35 in construction, it will be seen that it possesses the characteristic of absolute accuracy in determining the position of teeth in a denture relatively to the lip line of a patient. Only one adjustment is necessary for the instrument and, 40 after that adjustment has been made, there is no possibility of error being committed in calculating, so to speak, the lip line on the denture mold and, consequently, the final denture itself.

What I claim is:

45 1. In an instrument for determining the location of frontal teeth in a denture relative to the lip line of a patient, a bar, a lateral projection on said bar, a member adjustable on said bar relatively to said projection and adapted to be 50 positioned against the patient's gum with said projection in engagement with the lip of the patient to measure the distance between the gum and lip line, and means on said bar engageable in the gum engaging recess of the denture, the 55 location of said last-mentioned means relatively to a predetermined point on said adjustable

member corresponding to the relative positioning of said projection and the gum engaging portion of said member.

2. In an instrument for determining the location of teeth in a denture relative to the lip line 5 of a patient, a bar, means carried by said bar engageable against the patient's lip, a slide on said bar movable relatively to said lip engaging means adapted to be positioned against the patient's gum, and means on said bar engageable 10 in the gum recess of the denture, the distance between a predetermined point on said slide and the last-mentioned means corresponding to the distance between said lip engaging means and the 15 gum engaging portion of said slide. 15

3. In an instrument for determining the location of teeth in a denture relatively to the lip line of a patient, a bar, a lateral projection on said bar, a slotted sleeve on said bar movable relatively to said projection, one end of said sleeve 20 being adapted to be positioned against the gum of the patient with said projection positioned against the patient's lip, to denote the distance between the lip and gum, and means on said bar engageable in the gum recess of the denture, the 25 distance between said means and the opposite end of said sleeve corresponding to the distance between said projection and the first-mentioned end of the sleeve. 20

4. In an instrument for determining the location of teeth in a denture relatively to the lip line of a patient, a bar having one end curved to engage in the gum recess of the denture, a lip 30 engaging projection on said bar, and a sleeve 35 slidable on said bar projecting beyond the opposite end of the bar and adapted to engage against the patient's gum, the distance between said projection and the gum engaging portion of the sleeve substantially corresponding to the distance between a fixed point on said sleeve 40 and the curved extremity of said bar. 35

5. In an instrument for determining the location of teeth in a denture relatively to the lip line of a patient, a bar having an offset end portion 45 adapted to engage the bottom of the gum recess of a denture mold, a lateral projection on said bar adapted to be positioned against the patient's lip, a sleeve slidable on said bar adapted to be positioned against the patient's gum, and means on said sleeve for indicating the lip line 50 of the patient on said mold the distance between said last-mentioned means and the recess-engaging portion of said offset end corresponding to the distance between the gum-engaging portion of the sleeve and said lateral projection. 55
